UNITED STATES PATENT OFFICE.

JASON SMITH, OF ROCKLAND, MASSACHUSETTS.

MACHINE FOR TRIMMING, CHANNELING, AND GROOVING BOOT AND SHOE SOLES.

SPECIFICATION forming part of Letters Patent No. 270,498, dated January 9, 1883.

Application filed May 17, 1882. (No model.)

To all whom it may concern:

Be it known that I, JASON SMITH, of Rockland, in the county of Plymouth and State of Massachusetts, have invented new and useful 5 Improvements in Machines for Trimming, Channeling, and Grooving the Soles of Boots and Shoes, of which the following is a specification.

This invention consists of mechanism, fully 10 described below, whereby the sole is trimmed, channeled, and grooved at one and the same operation.

In the accompanying drawings, in which similar letters of reference indicate like parts, 15 Fig. 1 is a vertical section of the machine, not showing the carrier-block. Fig. 2 is a horizontal section of the machine on line $x-x$, Fig. 5. Fig. 3 is a vertical section on line $y-y$, Fig. 5. Fig. 4 is a plan of the under side of the 20 cam C and of the upper side of the stud E. Fig. 5 is a part rear elevation of the machine. Fig. 6 is a front view of the tool-holder removed. Fig. 7 is a side view of the same. Fig. 8 is a detailed sectional view of the swiv- 25 eled bar. Fig. 9 is a side elevation of the tool-holder and carrier-block, showing transverse vertical sections of the cam C, pattern, and sole being operated upon. Fig. 10 is a plan of the carrier-block. Fig. 11 is a vertical section 30 on line $z-z$, Fig. 10.

A represents the frame, A' being the hollow standard or supporting portion.

Loosely placed in the frame by means of its hub B' is the gear-wheel B, adapted to be engaged by the gear-wheel b, fixed to a horizontal shaft having bearings at a' a' in the arm a, extending from the frame. Fixed upon this shaft is also the clutch b', and loosely placed upon it is the pulley b'', connected with the 40 power.

A shunting mechanism for pressing the clutch b' against the pulley b'' to start the machine, and for removing the same for stopping it, consists of the lever e, having its lower end pivoted to the arm a, its upper end provided with a sleeve, c', encircling the shaft to which the clutch is fast, and connected by a spring, e'', to the arm a. The spring of course holds the clutch away from the pulley b''. The upper 45 end of the lever e is connected by the link d to the bent lever d', pivoted at d'', and having

a latch, e, pivoted to it, adapted to catch under the block or projection e' when the lever d' is down, said latch being held in such position by the spring e'', extending from the latch to 55 the projection e', as shown in Fig. 3. When the lever d' is down, therefore, the clutch b' and pulley b'' are engaged. When it is up they are disengaged.

C is a cam, provided on its under side with 60 two longitudinal slots, C', and a transverse slot, C''. (See Fig. 4.) In the longitudinal slots lie the studs or projections D, fixed to or integral with the gear-wheel B, and provided with extensions D', fitting into grooves C''' on 65 the under side of the slot, to insure rigidity. (See Figs. 1 and 4.) Into the transverse slot C'' extends the stud or block E, (lying longitudinally in the slot,) swiveled eccentrically on 70 the top of the shaft E' or on the wrist-plate 70 E'', fixed on said shaft, which is adapted to be turned by a hand-wheel, F, (reached through an opening in the standard A'), which is held in any desired position by means of set-screws F', passing through said standard. A block, 75 G, slotted to correspond with the slots C', lies immovably on the cam C, and is provided with a rib or shoulder, G', for the purpose below specified.

Upon the block G is the pattern-rest H, secured to the projections or pattern-rest supports D by means of screws H', and supporting the pattern f. The cam is provided with a groove, g, on its upper side. When the gear-wheel B is rotated, the stud E, lying on the 85 stationary wrist-plate E'' and in the slot C'' in the cam, produces by the aid of the projections D, which extend into the slots C', a longitudinal movement of the cam relative to the gear-wheel B as the cam rotates with said wheel. 90 This longitudinal movement is a reciprocating one, and the length of the throw at a given point is determined by the position of the stud E in the slot C''. When the stud is nearest the pattern-rest support or projection D next 95 the knives as it passes them as the cam rotates, the throw is greatest and the largest sole may be operated upon; when it is farthest from it at that point the throw is the least, and the smallest-sized soles may be operated upon. 100

Swinging horizontally from the arm A'' of the frame is an arm, h, the outer end of which

is provided with a ledge, *h'*, which lies under the edge or shelf *G'* on the block *G*, and assists to hold the tool-holder and knife-carrier block in place while at work.

5 Swiveled in the arm is a plate or disk, *I*, to which is rigidly secured a flat lever, *I'*, which rotates with the disk *I*. Projecting downward from this disk *I* (which with the lever *I'* makes practically one lever) are two rolls, *J*, which 10 extend into the cam-slot *g*. The parts *I I' J*, together with the frame *K*, pivoted at *K'* to the lever *I'*, and the curved guide-plate *k*, form the knife-carrier block. The knife-carrier or tool-holder *L* is pivoted to the knife-carrier block both above and below the knives—viz., at the point *l*, below the knives, directly to the carrier-block *K*, and at the point *l'* to the extension or arm *k'*, removable by turning a thumb-screw, *k''*, so as to remove the tool-holder, if desired. The tool-holder or knife-carrier *L* carries three knives—viz., the trimming-knife *M*, adjustably secured in a groove, *M'*, in the lower portion of the holder, and a channeling-knife, *N*, and grooving-knife *O*, both adjustably secured to an adjustable foot, *P*. The trimming-knife *M* is adjustable horizontally by means of the screw *1*. The channeling and grooving knives are adjustable relatively vertically by means of screws *2* and *3*, respectively, which 20 hold them to the foot *P*, and the gage *m*, also secured to the foot, is adjustable by means of the screw *5*. The foot *P* is adjustable vertically by means of the screw *4*, and is adapted to slide vertically on the foot holder or support *n*, and 25 said foot-holder *n* is adjustable horizontally in the tool-holder *L* by means of the nut or bolt *6*. The foot *P* (and knives carried therein) is adapted to be lifted away from the work by the foot-lifter *R*, which, thus doing, 30 presses a stiff spring, *r*, whose lower end lies in the foot and whose upper end rests in the frame *r'*, integral with the foot-holder *n*. As the cam is rotated the rolls *J* follow the track of the groove *g*, and the three knives above 35 mentioned trim, channel, and groove the sole *S* at one and the same operation by means of the mechanism above described. The pivoting of the tool-holder both above and below the knives to the carrier-block makes it very 40 stiff and firm during its work. A spring-bolt, *t*, is held forward by the spring *t'* in the barrel *t''* against the tool-holder behind the knives, as seen in Figs. 2 and 10, to hold them, with suitable tension, to their work. A pull-back 45 lever, *7*, provided with a catch, *8*, is for the purpose of drawing back the tool-holder when the pattern is being changed and holding it back by means of the hook *9*. When the machine is in operation the lever *7* lies back in a 50 rest, *10*, against the barrel *t''*, as in Figs. 3 and 10. 55

T is a trip-dog, projecting down far enough from the lever *11*, pivoted at *12* to the frame *A*, to reach the foot-lifter *R*. The lever *11* is 60 connected by the link *13* to the lever *14*, pivoted at *15* to the frame, and having its forward or free end bent up, so as to be struck

by the projection *B''* upon the hub *B'* of the gear-wheel *B*. The machine starts at the heel (which is to be trimmed only) with the foot-lifter *R* raised, (as in Fig. 3,) in order to draw up the grooving and channeling knives. When the cam has rotated sufficiently to turn the heel the projection *B''* strikes the free end of the lever *14*, bearing it down, and hence forcing the trip-dog *T* down, so that it strikes the foot-lifter *R*, which drops the grooving and channeling knives onto their work, and the remainder of the sole is operated upon by all three knives. (See Fig. 5.) The spring *16*, secured to the link *13* and frame, draws the levers and dog back to their original position. When the cam has completed its rotation and one sole has been operated upon, the machine is automatically stopped by reason of the projection *17*, which is placed on the under side of the cam in the position shown in Figs. 3 and 5, and which strikes the lever *18*, pivoted at *19*, and connected by a link, *20*, with the latch *e*, thus releasing the wheel *b''* from the clutch *b'*, as before described. 75 80 85 90 95

U is the clamp for holding the sole down upon the pattern. The clamp is supported by the bar *V*, swiveled on the vertical rod *V'*, surmounted by an adjusting-nut, *V''*, which is placed above the cross-bar of the frame *V'''*. The lower end of this frame *V'''* is connected by a knuckle-joint, *W*, (pivoted at *21* to the frame *A*), to a chain, *W'*, which passes over rollers *W''* to the treadle *W'''* at the lower end 100 of the frame-support *A'*. To press the clamp *U* down on the sole *S*, bear down the treadle *W'''*, which, by means of the knuckle-joint *W*, frame *V'''*, and bar *V*, swiveled on the rod *V'*, will accomplish the result. The side bars of 105 the frame *V'''* are swiveled on the top or cross bar of the same. (See Figs. 1, 3, and 5.) The spring *22* releases the sole when pressure is removed from the treadle. Provision for soles of different thicknesses is made in the adjusting-nut *V''*, which should be so situated as to keep the knuckle-joint always in a position to exert power when the treadle is down. The clamp *U* is held in the swiveled bar *V* by means of the slides *23*, provided with openings 110 *24*, which are made to coincide with openings *25* in the bar *V*, when the springs *26* are compressed. When in the above position the bent pins *27* on the clamp (see Fig. 1) are thrust into the coinciding holes *24* and *25* and the 115 springs *26* released. The bar *V* and slides *23* then assume the position seen in Fig. 8, the holes not coinciding, and the pins *27* on the clamp *U* are securely held. 120 125 130

The position of the machine when to be operated is as follows: The treadle *W'''* is raised, the knuckle-joint *W* back, the clamp *U* up above the pattern, and the heel end of the cam nearest the side of the frame having the carrier-block and tool-holder, the handle or lever *d'* is up, the gage *m* on the tool-holder bearing against the heel of the pattern *f*, and the foot-lifter *R* is up, drawing the knives *N O* away from the pattern. 135

To operate the machine, place the sole S on the pattern f, press down the treadle W''' to force the clamp U upon the sole, and press the lever d' down to start the machine. As the cam rotates the heel is first trimmed by the knife M; then the dog T is pushed down by the projection B'' on the gear-wheel, thus tripping the foot-lifter R and dropping the channeling and grooving knives N O upon the sole. The remainder of the sole is then trimmed, channelled, and grooved at once. When the starting-point is reached the latch e is lifted by the lever 18 and projection 17 and the machine stops. Then release the treadle W'''', raise the foot-lifter R, and remove the sole.

A machine has heretofore been provided with a longitudinally-moving bed or pattern carrying the sole, and with a pivoted carrier-frame carrying devices for molding, rounding, and channeling such sole, the said carrier-frame being arranged to move around the bed or pattern to perform the functions stated; but such is not my invention, and is not claimed by me.

Having thus fully described my invention, what I claim, and desire to secure by Letters Patent, is—

1. The combination of a supporting-frame, A, a pattern, f, rotated by mechanism on the frame, the pivoted carrier-block K, the knife-carrier L, pivoted to the carrier-block, and the knives M, N, and O, secured to the knife-carrier for trimming, channeling, and grooving the soles of boots and shoes at one operation, substantially as described.

2. In a sole-machine, the combination, substantially as hereinbefore described, of a pattern, f, rotated by mechanism on the supporting-frame, a pivoted carrier-block, K, and a tool-holder, L, carrying trimming, channeling, and grooving knives M, N, and O, and swiveled or pivoted to the carrier-block at points both above and below the knives.

3. In a boot and shoe sole machine, the combination, with a pattern, of a swiveled tool-holder, the trimming, channeling, and grooving knives M, N, and O, all secured to and carried by the tool-holder and operating mech-

anism, substantially as described, whereby the sole will be simultaneously trimmed, channelled, and grooved, as set forth.

4. The combination of a supporting-frame, A, an attached arm, A'', a swinging arm, h, supported by the latter, the pivoted carrier-block K, provided with the levers I I', and curved plate k, the tool-holder L, pivoted to the carrier-block, and provided with knives and the spring-bolt t, and barrel t', substantially as described.

5. The combination of the tool-holder L, provided with the foot P, and foot-lifter R, and the frame A, provided with the trip-dog T, connected by a system of levers, substantially as shown, with said frame, and adapted to be lowered by the contact of said levers with a projection, B'', on the under side of the gear-wheel B as it rotates with the cam and pattern, substantially as described.

6. The combination of the gear-wheel B, provided with the studs and extensions D D', adapted to support the pattern, the shaft E', provided with the wrist-plate E'' and stud E, and the sliding cam C, provided with the longitudinal slots C' and transverse slot C'', and slot g, constructed and arranged substantially as and for the purpose set forth.

7. The combination, with the clamp U, provided with the bent pins 27, of the swiveled bar V, provided with the spring-slides 23, having openings 24, for the purpose described.

8. The combination of the frame A, rod V', having the adjusting-nut V'', spring 22, frame V''', knuckle-joint W, and chain or cord W', all constructed and arranged substantially as and for the purpose set forth.

9. In a sole-machine, the combination of the cam C, its support, and a pattern, f, said cam having a longitudinal reciprocating movement in the same line on its support, and arranged to rotate with said support, substantially as described.

JASON SMITH.
